CLAIM

The ornamental design for an automobile, as shown and described.

DESCRIPTION

FIG. 1 is a front, right side perspective view of an automobile showing my new design, it being understood that the opposite side is substantially a mirror image thereof;

FIG. 2 is a rear, right side perspective view thereof, it being understood that the opposite side is substantially a mirror image thereof;

FIG. 3 is a top plan view thereof;

FIG. 4 is a right side elevation view thereof, it being understood that the opposite side is substantially a mirror image thereof;

FIG. 5 is a front elevation view thereof; and,

FIG. 6 is a rear elevation view thereof.
